UNITED STATES PATENT OFFICE.

DENNIS C. FAUSS, OF NEW YORK, N. Y.

DESIGN FOR A BUTTON.

SPECIFICATION forming part of Design No. 25,205, dated March 3, 1896.

Application filed January 24, 1896. Serial No. 576,740. Term of patent 7 years.

To all whom it may concern:

Be it known that I, DENNIS C. FAUSS, of New York city, in the county and State of New York, have invented and produced a new and original Design for a Button, of which the following is a full, clear, and exact specification.

Reference is to be had to the accompanying drawing, forming a part of this specification, in which the figure represents a plan view of a button, showing my design.

The design consists in a button having elliptical edge lines *a*, intersecting at their middles with the opposite sides of a circular line *b*. From the circular line *b* and at points between the edge lines *a* radial lines *c* project, said lines respectively projecting toward the points of junction of the edge lines *a* and serving to give the ends of the button a stellated appearance. Inclosed by the circular

line *b* is a representation or figure *d* characterized by the appearance of a cruciform element, at one end of which is displayed a loop and at the opposite end may be seen two parallel lines joined by a diagonal line.

25

An essential feature of my design resides in the elliptical edge lines *a* juxtaposed to the circular line *b* and in the lines *c* radiating from the circular line *b* and imparting a stellated appearance to the ends of the button. 30 The figure *d*, inclosed by the circular line *b*, is also an essential feature.

I claim—

The design for a button, substantially as shown and described.

DENNIS C. FAUSS.
